TYPE-BAR MECHANISM FOR TYPEWRITING MACHINES

Benjamin M. Daniel, Bridgeport, Conn., assignor to Underwood Corporation, New York, N. Y., a corporation of Delaware

Application December 15, 1951, Serial No. 261,796

2 Claims. (Cl. 197—37)

1

This invention relates to typewriting machines and more particularly to type-bar mechanisms for such machines, especially to type-bar mechanisms of the class wherein a case-shiftable type head is mounted upon a type bar. The invention is illustrated as embodied in the well known "Elliott Fisher" flat platen machine, such for example, as described in the patent to Sundstrand, No. 2,370,505.

It is an object of the present invention to provide an improved type-bar mechanism of the kind comprising a type head shiftably mounted on the outer end of a type bar.

It is a more specific object of the invention to provide a type-bar mechanism which constitutes an improvement over that described in the patent to Swanson, No. 2,480,979.

It is a further object of the invention to provide a type-bar mechanism of the kind comprising a type head shiftably mounted on the outer end of a type bar having a minimum number of parts subject to wear, and in which the weakest part may be readily replaced from time to time without removing the type bar from the machine.

These and further objects, features and advantages will become more readily apparent as the description of a preferred embodiment of the invention proceeds.

Referring now to the drawings:

Figure 1 is a view partly in side elevation and partly in section illustrating the mode of operation of the type bar of the present invention.

Figure 2 is an enlarged view partly in side elevation and partly in section showing the shiftable type head locked in position to enforce the printing of one of the types.

Figure 3 is a view similar to Figure 2 and showing the shiftable type head detented in position to enforce the printing of the other of its types, and

Figure 4 is a sectional view taken along the line 4—4 of Figure 2.

In the machine described in the above mentioned Sundstrand patent a plurality of type bars are mounted upon a semi-circular ring indicated herein at 10, forming part of the type carriage. The type-bar mechanism illustrated herein comprises a type bar 11 pivotally mounted at 12 upon a hanger 13 secured in a suitable manner to the semi-circular ring 10. An operating link 14 is pivoted to the lower end of the type bar and is selectively operable from the keyboard of the machine to swing the type bar 11 about its pivot 12 to imprint against a flat platen 15. A spring 55

2

16, operating through an arm 17 pivoted to the type bar, tends to hold said type-bar mechanism against a stop ring 18, as shown in full lines in Figure 1, and serves to return the bar to that position after each typing operation.

The upper end 19 of the type bar is flattened, and pivotally mounted upon the flattened portion, by means of a pin 20, is a type head 21. The type head is slotted to provide two legs 22 and 23 which closely embrace the flattened sides of the upper end of the type bar 10 to prevent side play of the type head with respect to the type bar. The bottom of the slot in the type head is straight as indicated at 24 to bear against a flat edge 25 of the end 19 of the type bar when the type head is in the Figure 2 position and to bear against a flat edge 26 of the end 19 when the type head is in the Figure 3 position.

An operating lever 27 is pivotally mounted between the legs 22 and 23 of the type head by means of a pin 28. The end 19 of the type bar is notched to provide a pair of surfaces 29 and 30 for cooperating with a nose 31 of the operating lever 27, and a light spring 32, extending between the type head and a free end 33 of the operating lever, holds the nose 31 of said lever against one or the other of the surfaces 29 and 30 when the type head is in an imprinting position. The surface 29 is at such an angle with respect to the pivot 20 that, when the type head is in the position shown in Figure 2, one side of the nose 31, in cooperation with the spring 32 and the surface 29, serves to lock the head in that position, which, as will be apparent from Figure 1, will cause a type 34 to strike against the platen 15 when the type bar is actuated. This locking action is brought about by the fact that attempted rotation of the type head from the Figure 2 position causes the nose 31 to exert its force along a line almost perpendicular to the surface 29. The surface 30 is sloped so that when the type head 21 is in its Figure 3 position, to locate a type 35 for imprinting against the platen, the lever 27, in cooperation with the spring 32 and surface 30, merely detents the head in this position without locking it.

Mounted in the type carriage of the machine in a suitable manner, for example as disclosed in the patent to Wise, No. 2,334,464, is a trip ring 36, selectively movable by suitable means from the normally elevated dot-and-dash line position to the full line position, as shown in Figure 1. With the ring 36 in its dot-and-dash line position, actuation of the type-bar mechanism causes the bar 11 to swing about its pivot and

strike the type 35 against the platen. When the trip ring 36 is moved to its full line position, actuation of the type-bar mechanism brings the free end 33 of the operating lever 27 into contact with said ring, and continued downward movement of the type bar forces the operating lever to swing the type head 21 from the position shown in Figure 2 to the position shown in Figure 3, the lock formed by the contact of the side of the nose 31 with the surface 29 being broken by the contact of the free end 33 of the operating lever with the trip ring 36. When the type bar returns to its home position the free end 33 of the operating lever contacts the stop ring 18 and forces the type head 21 to rock back from its Figure 3 position to its Figure 2 position, this movement being permitted by the fact that the type head is merely detented in its Figure 3 position and pressure against the free end of the lever 27 causes the nose 31 to cam off of the surface 30.

The weakest part of the present mechanism, and consequently the part which will wear out first, is the spring 32 and this spring may be readily replaced without removing the type bar from the machine. This ease of servicing the present mechanism constitutes a considerable improvement over the device of the Swanson patent, No. 2,480,979, referred to above. In the Swanson patent the lugs 83 and 92 are subject to considerable wear due to the reciprocating movement of the spring 78 and when these lugs become so worn, as they do after a relatively short while, that they will not support the spring 78, it is necessary to replace the entire type bar.

Having thus described the construction and advantages of the present invention, what is claimed is:

1. In a typewriting machine, a type bar having an end portion, a type head mounted upon said

end portion and movable from a first position to a second position, a type mounted in said type head in a position to engage a platen when said type head is in its first position, a second type mounted in said type head in position to engage a platen when said head is in its second position, an operating lever movably mounted on said type head, resilient means urging said operating lever toward said end portion, cooperating means on the said end portion and said operating lever serving in conjunction with said resilient means to detent said type head in one of its two positions, and other cooperating means on said end portion and said operating lever serving in conjunction with said resilient means to lock said type head in the other of its two positions.

2. In a typewriting machine, a type bar having an end portion, a type head pivotally mounted upon said end portion and swingable from a first position to a second position, a type mounted in said type head in a position to engage a platen when said type head is in its first position, a second type mounted in said type head in position to engage a platen when said head is in its second position, an operating lever pivotally connected at one end to said type head, and having a free end, a coil spring urging the free end of said operating lever toward said end portion of said type bar, cooperating means on the said end portion and said operating lever serving in conjunction with said spring to detent said type head in one of its two positions, and other cooperating means on said end portion and said operating lever serving in conjunction with said spring to lock said type head in the other of its two positions.

BENJAMIN M. DANIEL.
